UNITED STATES PATENT OFFICE.

WENZEL J. DVORAK, OF SUNSET HEIGHTS, TEXAS.

CONCRETE BUILDING CONSTRUCTION.

Application filed March 26, 1923. Serial No. 627,609.

To all whom it may concern:

Be it known that I, WENZEL J. DVORAK, a citizen of Czechoslovakia, residing at Sunset Heights, in the county of Harris and 5 State of Texas, have invented certain new and useful Improvements in Concrete Building Constructions, of which the following is a specification.

This invention relates to new and useful improvements in concrete building construction.

One object of the invention is to provide a construction of the character described whose parts are precast, previous to erection, said parts being provided with suitable reinforcing rods which project to form loops by means of which the parts may be tied together during the process of erection.

With the above and other objects in view the invention has particular relation to certain novel features of construction, arrangement of parts, and use, an example of which is given in this specification, and illustrated 20 in the accompanying drawings, wherein:—

Figure 1 shows a fragmentary horizontal sectional view of the construction.

Figure 2 shows a fragmentary vertical section view.

In the drawings the numerals 1 and 2 30 designate the vertical corner beams which are of a suitable contour to fit closely together, and the numeral 3 designates a wall column. These columns are mounted on a

suitable foundation as 4, and when a story 35 of the construction is completed a suitable cap plate as 5 is poured, this cap plate forming a support for an additional story. In the cap plate of the upper story bolts as

6 are embedded to receive the wooden strip 40 7 which is secured in place by the nuts 8. This wooden strip is provided for nailing the rafters or other roof support to the structure. The columns 1, 2 and 3 have

suitable vertical reinforcing rods as 9 and 45 horizontally arranged reinforcing rods as 10, 11, 11, 12, 12, and 13 which project out forming loops or ties, as illustrated in Figure 1. The walls are composed of

50 outer wall slabs 14, 14 and inner wall slabs 15, 15 spaced apart and reinforced with the reinforcing rods 16 and 17 respectively. These reinforcing rods of the wall slabs project out at the ends forming the loops

55 10', 10', 11', 11', 12', 12', and 13', 13', which overlap the corresponding loops 10, 11, 12

and 13, respectively, and the parts are interlocked or tied together by the corresponding tie rods 18, 18, 19, 20, 20, and 21, 21, and when erected in position concrete in plastic state is poured in between the adjacent walls to embed said overlapping loops and locking rods in the material of the wall and when this concrete is hardened it will form a substantially monolithic structure. The 60 reinforcing rods 9 have their lower ends embedded in the foundation as well as in the cap plate of the wall, thus tying the parts together and forming a very strong construction. The wall slabs 14 and 15 are 65 mounted one upon the other, as shown in Figure 2. These slabs are preferably about two feet in width and of the required length and thickness and when mounted in place with their ends anchored to the columns of 70 the framework, as described, and as shown in Figures 1 and 2 they form a smooth and durable wall substantially hollow throughout thus providing a building whose interior 75 is not suddenly affected by variations in the outside temperature.

What I claim is:—

1. A concrete construction composed of a base, precast concrete columns mounted on said base and forming corner columns and 85 wall columns, vertical reinforcing rods embedded in said columns whose lower ends project beyond the columns and are embedded in said base, precast concrete wall slabs disposed one above the other forming 90 outer and inner walls horizontally arranged, reinforcing rods in said projecting columns and slabs which are formed into projecting loops which project from adjacent parts of the columns and slabs and overlap, locking rods projecting through said loops and locking them together, the upper ends of the vertical reinforcing rods of said columns projecting beyond the columns, and a cap plate molded onto the top of the complete 95 wall of said construction, the said projecting upper ends of said rods being embedded in said cap plate.

2. A concrete construction composed of a base, precast vertical corner columns, and 100 precast vertical wall columns, said corner columns being formed of vertical sections formed to complement each other, and said columns being mounted on said base, vertical reinforcing rods embedded in said columns and whose lower ends project into the base, horizontally arranged reinforcing 110

rods in said respective columns which project out, forming loops or ties, and loops projecting from the respective sections of the wall columns and, over-lapping, outer 5 wall slabs and inner wall slabs spaced apart, longitudinal reinforcing rods embedded in said slabs and formed with projecting end loops which overlap the corresponding loops of the horizontal reinforcing rods of the 10 columns, vertical tie rods inserted through said respective overlapping loops and locking said parts together, said vertical rein-

forcing rods projecting up above said columns, and a cap plate moulded onto the top of the complete wall of the construction, 15 said projecting upper ends of said rods being embedded in said cap plate.

In testimony whereof I have signed my name to this specification in the presence to two subscribing witnesses.

WENZEL J. DVORAK.
